Atty.

UNITED STATES PATENT OFFICE.

CHRISTOPHER BROWN, OF CHARLEROI, PENNSYLVANIA, ASSIGNOR TO PITTSBURGH PLATE GLASS COMPANY, A CORPORATION OF PENNSYLVANIA.

EDGE GRINDING AND POLISHING MACHINE.

1,380,133.

Specification of Letters Patent. Patented May 31, 1921.

Application filed September 27, 1918, Serial No. 255,885. Renewed December 10, 1920. Serial No. 429,809.

To all whom it may concern:

Be it known that I, CHRISTOPHER BROWN, a citizen of the United States, and a resident of Charleroi, in the county of Washington and State of Pennsylvania, have made a new and useful Invention in Edge Grinding and Polishing Machines, of which the following is a specification.

The invention relates to machines for grinding or polishing the edges of circular glass or stone plates or sheets. It has for its principal objects the provision of a machine in which the plate of material being operated upon is securely maintained in centered position with a relatively slight application of clamping force; the provision of a machine wherein the labor of centering the sheet of material is reduced; and the provision of a machine having improved and simplified means for applying the abrading element to the edge of the plate of material. One embodiment of the invention is illustrated in the accompanying drawings wherein:

25 Figure 1 is a side elevation of the machine with the lower portion thereof partially in section and Fig. 2 is a transverse section on the line II-II of Fig. 1.

Referring to the drawings 1 is the frame-work of the machine provided with the laterally projecting bracket 2. Mounted above the bracket is the driving mechanism comprising the cone pulley 3 driven from the belt 4 and the train of reducing gearing 5 for driving the beveled gear 6. This beveled gear drives the beveled gear 7 through which is splined the operating spindle 8 of the machine.

The spindle is swiveled in the raising and lowering member 9 provided on its rear side with the rack 10 which is moved up and down by means of the pinion 11. As indicated in Fig. 2 the pinion 11 is mounted upon the shaft 12 carrying at one end the hand-wheel 13 and at the other end the lever 14 which is loosely mounted upon the shaft. The extreme end of the shaft carrying the lever is provided with a toothed wheel 15 adapted to be engaged by the latch member 16 extending longitudinally of the lever and normally held in advanced position by means of a spring (not shown). The latch member is retracted by means of a handle 17.

55 The sheet of glass or stone 18 (Fig. 1)

is held between the clamping members 19 and 20, such members being faced with felt or other fibrous material to increase their grip upon the sheet and to prevent marring it. The clamping member 19 is carried by the lower end of the spindle 8 while the member 20 is carried upon the upper end of the spindle 21, such spindle being mounted in the bearings 22 and 23 as illustrated.

After the sheet of material 18 is centered between the clamping members, the driving mechanism is thrown into operation to cause the rotation of the spindle 8 and the consequent rotation of the clamping members 60 and the sheet held therebetween. The abrading means are then applied to the edge of the sheet in the form of the block 24 carried by the lever 25. This lever is removably mounted in the box 26 which surrounds the clamping members, its fulcrum being in the corner of the box 27 as indicated in Fig. 2. The block 24 may be of any kind of abrading material, such for instance as carborundum, the box 26 serving 65 to catch the particles of abrasive and any liquid which may be employed as well as the material which is ground off the edge of the sheet under treatment.

The lever 14 serves to give a raising and 70 lowering movement of limited extent to the clamping member 19 and for the application of pressure to maintain the proper clamping engagement between the clamping members and the sheet or plate of material. The lever 14 is held in clamping position by the weight 28 hung removably thereon. When it is desired to move the rack and clamping member up a substantial distance the lever 14 is released from the toothed member 75 15 and the hand-wheel 13 is employed to give the necessary upward movement. The weight of the sheet or plate 18 tends to maintain it in centered position between the clamping members, which is not the 80 case where the sheet is rotated in a vertical plane, as has heretofore been common, and the amount of clamping pressure by the clamping member 19 required in order to give the sheet the necessary movement of 85 rotation is not great, such pressure being supplied by the weight of the parts including that of the spindle and the parts attached thereto and the weight carried by the operating lever 14. It is also comparatively 90 100 105 110

easy to center the sheet of material as it is easily shifted upon the member 20 to proper position before the member 19 is applied. The lever 25 also serves as a simple and convenient means for applying abrading pressure to the edge of the sheet since the lever has universal movement and can be instantly removed when desired in order to change the block 24 as conditions may require. The edge of the sheet may be ground, smoothed and polished without removing it from the machine. Other advantages incident to the construction will be readily apparent to those skilled in the art.

15 What I claim is:

1. In combination in a machine for grinding or polishing the edge of circular plates which comprises a pair of opposing clamping members rotatable about a vertical axis, an operating spindle for the upper one of said members located on said axis, a raising member provided with a rack in which said spindle is swiveled, a pinion meshing with the rack, and means for rotating the spindle.
- 20 2. In combination in a machine for grinding or polishing the edges of circular plates which comprises a pair of opposing clamping members rotatable about a vertical axis, an operating spindle for one of said members located on said axis, a pinion for raising and lowering the upper clamping member, a lever for rotating the pinion and normally applying pressure to lower such upper clamping member, and means for rotating said spindle.
- 25 3. In combination in a machine for grinding or polishing the edges of circular plates which comprises a pair of opposing clamping members rotatable about a vertical axis, an operating spindle for the upper of said clamping members located on said axis, a pinion for raising and lowering said spindle, a lever for rotating the pinion and normally applying pressure to lower the spindle, and means for rotating the spindle.
- 40 4. In combination in a machine for grinding or polishing the edges of circular plates

which comprises a pair of opposing clamping members rotatable about a vertical axis, an operating spindle for the upper of said clamping members located on said axis, a pinion for raising and lowering said spindle, a lever for rotating the pinion and normally applying pressure to lower the spindle, a hand-wheel for rotating the pinion, and means for rotating the spindle.

5. In combination in a machine for grinding or polishing the edges of circular plates which comprises a pair of opposing clamping members rotatable about a vertical axis, an operating spindle for the upper of said clamping members located on said axis, a pinion for raising and lowering said spindle, a lever for rotating the pinion, means whereby the lever may be adjusted circumferentially with respect to the pinion and fixed with respect thereto in its various positions of adjustment, and means for rotating the spindle.

6. In combination in a machine for grinding or polishing the edges of circular plates which comprises a pair of opposing clamping members rotatable about a vertical axis, an operating spindle for the upper of said clamping members located on said axis, a pinion for raising and lowering said spindle, a lever for rotating the pinion, means whereby the lever may be adjusted circumferentially with respect to the pinion and fixed with respect thereto in its various positions of adjustment, or released, other means for rotating the pinion, and means for rotating the spindle.

7. In combination in a grinding or polishing machine, a pair of opposing clamping members rotatable about a vertical axis, an operating spindle for the upper member, a lever for raising and lowering the spindle, and a weight releasably mounted upon the lever to apply the necessary clamping force.

In testimony whereof, I have hereunto subscribed my name this 18th day of September, 1918.

CHRISTOPHER BROWN
